UNITED STATES PATENT OFFICE

CLARENCE E. LOMAX, OF OAK PARK, ILLINOIS, ASSIGNOR TO RESERVE HOLDING COMPANY, OF KANSAS CITY, MISSOURI, A CORPORATION OF DELAWARE

AUTOMATIC TELEPHONE SYSTEM

Application filed April 16, 1927, Serial No. 184,197. Renewed January 12, 1929.

The present invention relates to automatic telephone systems in general, but is concerned more particularly with the circuit arrangements of an improved two-way trunk circuit 5 for use in connecting two automatic exchanges.

The principal object of the invention is to eliminate the noise from the talking circuit of an inter-exchange trunk line which is subject to inductive interference or disturbances 10 from high tension circuits or other high powered circuits. This is accomplished by removing the battery and ground connections from the talking conductors of the trunk line 15 when the called party answers.

According to a feature of the invention, the called party is fed talking battery from the local connector on local calls and on inter-office calls the battery at the connector is disconnected and the called party is fed talking battery from the repeater.

Another feature of the invention relates to the novel circuit arrangements by means of which the calling subscriber controls the 25 release of the automatic switches in the distant exchange.

Another feature of the invention consists in the provision of an improved automatic switch for use in private automatic exchanges, 30 the switch being of a type which is commonly known as a "switching through" connector.

The foregoing and other improvements will be described fully hereinafter, reference being had to the accompanying drawings.

Referring to the drawings, comprising 35 Figs. 1, 2, and 3, there is shown by means of the usual circuit diagrams sufficient of the apparatus in the system to enable the invention to be explained and understood.

In Fig. 1 there is shown at A an automatic substation of a well known type. The line of substation A terminates in the usual manner in connector bank contacts and an individual rotary lineswitch such as indicated by 40 reference character LS¹. The lineswitch LS¹ is of the well known rotary type in which the wipers have no normal position and which have access to selector switches such as indicated by the reference character S¹. The selector S¹ is of the well known vertical and

rotary type of Strowger switch and has access to outgoing repeaters such as OR¹ and has access to connector switches such as connector C¹. The connector C¹ is of the well known vertical and rotary type Strowger switch 55 and has access to the automatic subscriber's lines such as the line of substation A.

The outgoing repeater OR¹ may be accessible from the "O" level of the selectors such as S¹ and is used for extending calls over 60 the trunk comprising conductors 30 and 31 to a distant automatic exchange.

Incoming calls from the distant automatic exchange extend over conductors such as conductors 30 and 31 to incoming repeaters such as repeater IR¹. Repeater IR¹ is similar to the repeater IR² in Fig. 2. Associated with each incoming repeater IR¹ there is shown an incoming selector switch IS¹ which is of the well known vertical and rotary type of 70 Strowger switch. The incoming selector switch IS¹ has access to the connectors such as C¹. The bank contacts of the incoming selectors are multiplied with the bank contacts of the first selectors such as S¹. 75

In Fig. 2 the trunk line comprising the conductors 30 and 31 terminates in the distance automatic exchange in the repeater OR² which is similar to the repeater OR¹ in Fig. 1 and also in the incoming repeater IR² which is 80 similar to the incoming repeater IR¹ in Fig. 1. The outgoing repeater OR² is used for extending outgoing calls while the incoming repeater IR² is used only for incoming calls.

A number of relays are shown in the incoming 85 repeater IR², the circuit arrangement of which permits certain novel operating features to be performed. Associated with the incoming repeater IR² there is shown an incoming selector IS² which has access to connectors such as connector C², Fig. 3. The connector C² is a vertical and rotary switch of the well known Strowger type so far as mechanical construction is concerned, the circuits of which, however, have been somewhat improved as will appear more clearly hereinafter. The connector C² is also accessible 95 from the first selectors such as S² and is also used for completing local connections. The 100

connector has access to automatic subscribers such as shown at substation A².

The substation A² is similar to substation A¹ and is of the well known automatic type having the usual calling device, talking instrumentalities, and ringer. The line of substation A² terminates in an individual rotary lineswitch LS² which is of the well known rotary type. The lineswitch LS² is similar to the lineswitch LS¹ in Fig. 1 and has access to first selectors such as selector S². The selector S² is similar to the selector S¹ in Fig. 1 and has access to the outgoing repeaters OR² and the connectors such as connector C².

Having described the apparatus involved in the operation of the same will now be explained more in detail. For this purpose it will be assumed that the subscriber at substation A, Fig. 1, desires to establish a connection with the subscriber at substation A², Fig. 3. When the receiver is removed at substation A a circuit is closed over the line for the line relay of the lineswitch LS¹ whereupon the lineswitch, in a well known manner, selects an idle trunk extending to a selector. It will further be assumed that the selector S¹ is the selector seized by the lineswitch LS¹ and that the subscriber at substation A, by the operation of his calling device, operates the selector S¹ to the group of bank contacts in which the outgoing trunks to the desired exchange terminate and that the selector S¹ seizes the outgoing repeater OR¹. The selector S¹, in switching through in the well known manner, closes a circuit for energizing the line relay 6 of the repeater OR¹ over the subscriber's loop. The circuit may be traced as follows: from ground, by way of the lower winding of line relay 6, lower left-hand winding of the repeating coil, bank contact 23, the subscriber's loop including the wipers of the line switch LS¹ and selector S¹, bank contact 21, upper left-hand winding of the repeating coil, to the upper winding of line relay 6 and battery. At armature 14 relay 6 closes a circuit for energizing slow-to-release relay 7. The latter relay energizes and at armature 15 causes slow-to-release relay 9 to energize. At armature 16 relay 7 opens the circuit of relay 8 and at armature 17 prepares a circuit for series relay 5. Relay 9, upon energizing, at armature 19 grounds the release trunk conductors 24 thereby maintaining the selector S¹ and lineswitch LS¹ in operated position and at the same time guards the outgoing repeater OR¹ from seizure by other selectors in the well known manner. At armatures 18 and 20 the trunk conductors 30 and 31 are disconnected from the incoming repeater IR¹ and are connected instead to the right-hand winding of the repeating coil. When the trunk conductors 30 and 31 are connected to the right-hand windings of the repeating coil in the repeater OR¹, a circuit may be traced for energizing the line relay 47 of the in-

coming repeater IR² as follows: from ground, by way of the lower winding of line relay 47, armature 55, lower left-hand winding of the repeating coil, conductor 41, armature 20', conductor 31, armature 20, lower and upper-right hand windings of the repeating coil, armature 13, armature 18, conductor 30, armature 18', conductor 40, upper left-hand winding of the repeating coil, armature 54, to the upper winding of line relay 47 and battery. Line relay 47, upon energizing, at armature 57 closes a circuit for energizing release relay 48 and at armature 56 closes a circuit for energizing series relay 50 and the line relay of the incoming selector IS² as follows: ground by way of armature 63, armature 56, series relay 50, back contact and armature of the switching relay in the selector IS², to the upper winding of the line relay of the selector and battery. At armature 58 relay 48 grounds the release trunk conductor 24' thereby guarding the outgoing repeater OR² from seizure by selector switches such as selector S², Fig. 3. Relay 50, upon energizing, closes a circuit for energizing relay 51 and the latter relay prepares a circuit for relay 52. The outgoing repeater OR¹, the incoming repeater IR², and the incoming selector IS² are now in readiness to receive the impulses of the next digit of the called number.

Responsive to the operation of the subscriber's calling device the circuit of the line relay 6 is interrupted a plurality of times whereby said relay is deenergized a corresponding number of times. Upon the first deenergization of relay 6 a circuit is closed for energizing relay 5 at armature 14. Relay 5 is energized and at armatures 10, 11, and 12 shorts out both windings of the repeating coil in order to improve the impulsing circuit. Both relays 5 and 7 are slow acting and therefore maintain their armatures attracted during impulsing. At armature 13 line relay 6 opens the bridge across the trunk conductors 30 and 31 thereby opening the circuit of line relay 47 of the incoming repeater IR².

Each time the line relay 6 of the repeater OR¹ interrupts the bridge across the trunk conductors 30 and 31 at armature 13 of the line relay 47 of the incoming repeater R² is deenergized. The latter relay at armature 56 interrupts the circuit of the line relay of the selector IS² a like number of times whereupon said selector is operated in the vertical direction in the well known manner to select the desired group of trunk lines extending to the proper group of connectors. The incoming selector IS² now rotates in the well known manner to select an idle connector in the selected group. It will now be assumed that the connector C² shown in Fig. 3 is the connector seized by the incoming selector IS². The seized connector C² is made busy to selector switches such as selectors IS² and

S² from ground at armature 58 which extends through the incoming selector IS² to wiper 64 and thence by way of bank contact 67 to conductors 70 and 170 and multiples thereof. When the selector IS² seizes the connector C² the switching relay in the selector IS² closes a circuit for the line relay 100 of the connector C² as follows: ground by way of armature 63, armature 56, series relay 50, the upper talking conductor of the selector IS², wiper 63, bank contact 66, conductor 69, armature 115, and upper winding of line relay 100 to battery. The line relay energizes over the above traced circuit and closes an energizing circuit for release relay 101. Release relay 101, upon energizing, at armature 113 closes a circuit for short circuiting the lower winding of relay 106, said short circuit including the grounded release trunk conductor 70. At armature 114 release relay 101 opens a point in the circuit of the release magnet 110 and prepares a circuit for the series relay 102 and the vertical magnet. The connector C² is now ready to receive the impulses of the next digit of the called number.

When the calling subscriber at substation A operates his calling device in accordance with the next digit of the called number the impulses are repeated from the outgoing repeater OR¹ to the incoming repeater IR² in the same manner as previously described. Line relay 47 in the repeater IR² now interrupts the circuit of the line relay 100 of the connector C² whereupon said relay deenergizes for each impulse. Release relay 101 being slow acting does not release during impulses and therefore a circuit may be traced for the series relay and vertical magnet when the line relay 100 deenergizes on the first impulse: ground by way of the armature of line relay 100 and its resting contact, armature 114, and its working contact, normally closed off normal springs 150, series relay 102, and vertical magnet 109 to battery. Upon the first vertical movement of the switch the off-normal springs 150 are shifted and the remaining impulses to the series relay and vertical magnet are transmitted over a new circuit which includes the normally open off-normal contacts and the armature and working contact of relay 102. Relay 102 being a slow-acting relay maintains its circuit intact during impulses. By the operation of the vertical magnet 109 the switch wipers 141, 142, and 143 are raised step by step and are finally brought to rest opposite the level in which the line of substation A² is terminated. At the end of the vertical movement relay 102 deenergizes and transfers the impulsive circuit to the rotary magnet 111. The calling subscriber may now call the next and last digit in the desired number. As before, a series of interruptions are repeated to the line relay 100 and the line relay 100 is deenergized a plurality of times and sends a series of impulses to the rotary magnet 111: ground by way of the line relay armature and its resting contact, armature 114 and its working contact, normally open springs controlled by the off-normal spring 150, armature of series relay 102 and its resting contact, series relay 107, armature 138, armature 125, and winding of rotary magnet 111 to battery. By the operation of the rotary magnet 111 the switch wipers are rotated step by step and are finally brought to rest in engagement with the particular set of contacts in which the line of substation A² is terminated, these contacts being indicated in the drawing by reference characters 144, 145, and 146. The slow-acting series relay 107 is energized in series with the rotary magnet and maintains its armatures attracted throughout the rotary movement. At armature 132 the series relay 107 opens the circuit of the switching relay 108 and prepares a circuit including the busy relay 105 for testing the called line and at armature 133 maintains its own circuit and the circuit of the rotary magnet 111 independent of armature 125. The operation of the connector C² now depends upon whether the called line is busy or not.

It will now be assumed that the line of substation A² is busy when called. Under these circumstances there will be a ground potential upon the test contact 145 and when the test wiper 142 comes to rest in engagement therewith the busy relay 105 will be energized over a circuit as follows: ground on the test contact 145, test wiper 142, armature 132 and its working contact, resistance 180, armature 121, and winding of busy relay 105 to battery. Shortly after the impulses cease the slow-acting series relay 107 deenergizes and completes a locking circuit for the busy relay as follows: ground by way of grounded release trunk conductor 70 low resistance winding of relay 106, armature 124 and its working contact, normally closed springs controlled by armature 132, and thence over the previously traced circuit to the upper winding of busy relay 105. It may be mentioned at this time that the resistance 180 in the above locking circuit is of such resistance as to maintain the busy relay 105 energized but is too high to permit relay 106 to energize. In addition relay 106 is still short circuited from ground at armature 113. At armature 125 the busy relay opens the circuit of the rotary magnet 111 and at armature 126 closes a circuit for energizing relay 103 as follows: grounded conductor 70, armature 129, armature 134, armature 126, and winding of relay 103 to battery. Relay 103, upon energizing, at armature 115 opens the circuit of the line relay 100 and at armature 117 opens a point in the release magnet circuit so that the switch will not be released when the line relay 100

and release relay 101 deenergize shortly after the circuit of the line relay is opened at armature 115.

When the armature 115 opens the circuit of line relay 100, it also opens the circuit of series relay 50 in the incoming repeater IR^2 whereupon the latter relay deenergizes. Relay 50, upon deenergizing, closes a circuit for energizing switching relay 52 whereupon said relay energizes and closes a locking circuit for itself which includes the grounded armature 58. At armatures 60 and 62 relay 52 connects the talking conductors 42 and 43 of the incoming repeater IR^2 to the talking conductors 69 and 70 of the connector C^2 , and at armature 63 disconnects ground from armature 56.

Returning now to the connector C^2 , a circuit may now be traced for transmitting an audible busy signal to the calling subscriber. The busy signalling circuit includes the armature 127 of the busy relay 105, armature 130, armature 123, lower talking condenser, talking conductor 71, the right-hand windings of repeating coils in repeater IR^2 , armature 60, to ground at armature 56. By means of the repeating coils the calling subscriber is given the busy tone in the well known manner.

When the calling subscriber hears the well known busy tone, he will replace his receiver thereby opening the circuit of the line relay 6. At armature 13 relay 6 opens the bridge across the trunk and at armature 14 opens the circuit of release relay 7 whereupon the latter relay deenergizes. At armature 15 the circuit of relay 9 is opened and said relay releases. Due to relays 7 and 9 being slow acting, relay 9 does not deenergize and remove the guarding ground from release trunk conductor 24 until a considerable time after the bridge across the conductors 30 and 31 is opened at armature 13. This arrangement is provided to prevent the seizure of the trunk line until all the apparatus in both exchanges has had sufficient time to release. By the removal of ground from conductor 24 the lineswitch LS^1 and selector S^1 are released in the well known manner.

When the bridge across the trunk is opened at armature 13 line relay 47 in the incoming repeater IR^2 deenergizes and opens the circuit of release relay 48 whereupon the latter relay deenergizes. At armature 58 release relay 48 opens the locking circuit of relay 52 whereupon the latter relay deenergizes. At armature 58 relay 48 also removes ground from release trunk conductors 24' and 70 whereupon the incoming selector is released in the well known manner and the circuits of the busy relay 105 and relay 103 are opened. Busy relay 105 and relay 103 deenergize and the latter relay at armature 117 closes an energizing circuit for the release magnet 110 whereupon the connector is released in the

well known manner. All the apparatus used in extending the connection is now in normal position and may be used for other calls.

Having explained what occurs when the called line is busy, it will now be assumed that the called line is idle. Such being the case, when the test wiper 142 comes to rest in engagement with the test contact 145, it will find no ground potential and the busy relay 105 will not be energized. Instead, when the slow acting relay 107 falls back, a circuit is closed through the upper winding of the switching relay 108 as follows: from ground by way of armature 113, armature 124 and its resting contact, upper winding of switching relay 108, armature 132, test wiper 142, test contact 145, conductor 147, and winding of the cut-off relay of the lineswitch LS^2 to battery. Upon the closure of the above traced circuit the cut-off relay of the lineswitch LS^2 is operated to clear the line of substation A^2 from its normal battery and ground connection in the lineswitch LS^2 . This is accomplished by the well known mechanical interlocking arrangement of the rotary lineswitch LS^2 . In the connector C^2 , when the switching relay 108 is energized it closes a locking circuit for itself which includes the lower winding, armatures 137 and 136 and the grounded release trunk conductor 70. In addition armature 136 connects the grounded release trunk conductor 70 to the test wiper 142 thereby connecting a guarding potential to test contact 145 and multiples thereof. At armature 138 relay 108 opens the circuit of relay 107 and rotary magnet 111 and at armature 139 completes a circuit for energizing relay 103. The circuit for energizing relay 103 includes the grounded release trunk conductor 70, armature 129, armature 134, armature 139, and the winding of said relay. At armatures 135 and 140 switching relay 108 connects interrupted generator to the called line.

Before proceeding with the ringing operation it should be mentioned that relay 103 upon energizing opens the circuit of the line relay 100 at armature 115 and at armature 117 opens a point in the circuit of the release magnet 110 so that that magnet will not be energized when the line and release relays shortly deenergize. At armature 115 relay 103 also opens the circuit of relay 50 which thereupon deenergizes and causes the relay 52 to energize and lock in the same manner as previously described. The release of relays 100 and 101 are without effect at this time other than to prepare the release circuit which is now open at armature 117.

The connection to the desired line has now been completed and ringing current from the generator, Int. Gen., is intermittently projected out over the line to operate the ringer at the substation A^2 . The ringing circuit may be traced as follows: from ground by way of

5 armature 122, armature 140, wiper 143, contact 146, the bridged ringer and condenser at the substation A², bank contact 144, wiper 141, armature 135, armature 119, lower winding of ring cut-off relay 104, to interrupted generator Int. Gen. The ringing current passing through the lower winding of ring cut-off relay 104 induces a current in the upper winding of said relay which forms a 10 circuit through the lower winding of busy relay 105, armature 123, lower talking condenser, through the lower talking conductor of the connector over the previously traced busy signalling circuit to ground at armature 15 56, for transmitting the well known ring back tone to the calling subscriber each time the called party's bell is rung.

When the called party answers the ring cut-off relay 104 energizes and at armature 20 120 completes a locking circuit for itself which includes the grounded release trunk conductor 70. Ring cut-off relay at armature 123 opens the ring back circuit and at armatures 119 and 122 opens the ringing circuit. At the same armatures relay 104 connects the talking conductors of the called line straight through to the talking conductors of the incoming repeater IR² independent of any ground or battery connections at 25 30 the connector C². When the line of the called subscriber A² is connected through to the incoming repeater IR² the back bridge relay 45 in the incoming repeater IR² is energized and said relay closes a circuit by way of armature 59 for energizing relay 46. Relay 46, upon energizing, at armature 53 closes a circuit for energizing relay 49 and the latter relay connects ground to the release trunk conductor 24' so as to maintain ground on 35 40 said conductor after relay 48 deenergizes which it does shortly hereafter. At armatures 54 and 55 and their resting contacts relay 46 opens the circuit of line relay 47 thereby removing all battery and ground connections from the inter-office trunk, and at 45 50 armature 55 and its working contact substitutes a high resistance bridge for the battery and ground connections of the line relay. The line relay 47 deenergizes and also causes release relay 48 to deenergize and open the original energizing circuit of relay 46 at armature 59, but the latter relay is maintained energized by way of resistance 44 which is connected in shunt of armature 59. By the 55 60 removal of battery and ground from the inter-office trunk the inductive disturbances caused by close high tension circuits is eliminated thereby rendering an efficient talking circuit over a trunk line which otherwise would be very poor on account of the inductive disturbances. The connection now having been completed the calling and called subscribers may converse with each other as desired.

65 After conversation and responsive to the

replacement of the receiver by the calling subscriber at substation A the circuit of line relay 6 is opened and said relay and release relay 7 deenergize. Shortly after release relay 7 deenergizes relay 9 also deenergizes and removes the guarding ground at armature 19 so as to render the inter office trunk selectable. It will be noted that this ground is maintained for an interval in order to allow all the apparatus which is connected to the trunk to be properly released before it can again be selected. By the removal of ground from the release trunk the selector S¹ and the lineswitch LS¹ are released in the well known manner.

When release relay 7 deenergizes a circuit may be traced through the upper winding of differential relay 46 as follows: ground by way of armature 14 and its resting contact, armature 17 and its resting contact, armature 20, conductor 31, armature 20', conductor 41, lower left-hand winding of the repeating coil, armature 55 and its working contact, upper winding of differential relay 46, upper left-hand winding of the repeating coil, conductor 40, armature 18', conductor 30, armature 18, armature 16, and winding of relay 8 to battery. Relay 46 immediately deenergizes because the direction of current flow in the upper winding of relay 46 is in opposition to that through its lower winding. It should be explained that resistance 44 is high enough to prevent relay 46 from again energizing when relay 9, Fig. 1, falls back. Relay 46, upon deenergizing, at armature 53 opens the circuit of relay 49 whereupon the latter relay deenergizes and removes ground from release trunk conductor 24' thereby opening the circuits of relays 103, 104, and 108 and permitting the selector IS² and connector C² to release in the manner as previously described. All the apparatus in the originating exchange is now in normal condition and may be used for extending other calls.

In case the called subscriber at substation A² is the first to replace his receiver the circuit of relay 45 in the incoming repeater R² is opened and said relay releases and opens the circuit of relay 46. Relay 46, upon releasing, at armature 53 opens the circuit of relay 49 whereupon said relay releases and removes ground from the release trunk 24'. However, before said ground is removed line relay 47 is again energized over the trunk line and release relay 48 again applies ground at armature 58 to release trunk conductor 24' thereby maintaining the selector IS² and connector C² in operated position. If the calling subscriber should replace his receiver under the above conditions the circuit of the line and release relays would be opened in an obvious manner and the switches returned to their normal positions.

The automatic subscriber at substation A² may call the automatic subscriber at substa-

tion A, Fig. 1, in the same manner as just previously explained with the exception that the lineswitch LS², the selector S², the outgoing repeater OR², which is identical to the outgoing repeater OR¹, the incoming repeater IR¹ which is identical to the repeater IR², the incoming selector IS¹, and the connector C¹ which is identical to connector C² is used for extending and completing the call to the subscriber at substation A.

Having described how inter-exchange calls are completed a description will now be given of the apparatus used in completing local calls. For this purpose it will be assumed that an automatic subscriber in the same exchange as substation A² desires a connection with the subscriber at A². The calling subscriber's lineswitch is operated in the well known manner responsive to the removal of the receiver and by the operation of his calling device the calling subscriber causes the first selector to seize an idle connector which has access to the line of the desired subscriber or substation A². It will further be assumed that the selector has seized the connector C² over the conductors 169, 170, and 171. When the selector seizes the connector C² the line relay 100 and release relay 101 energize in the manner previously described and the latter relay at armature 113 prepares the circuit for relay 106. Due to ground being momentarily sent forward over conductor 170 from the selector S² relay 106 is not at this time energized. However, when the release relay of the selector deenergizes after the selector switches through in the well known manner ground will be removed from conductor 170 whereupon a circuit may be traced from ground at armature 113, lower winding of relay 106, release trunk conductor 170, wiper of the selector, and through the winding of the switching relay to battery over the well known circuit. Relay 106 energizes over this circuit and the switching relay is maintained in energized position. At armature 128 relay 106 completes a locking circuit for itself and at armature 129 and its working contact shunts out the lower winding thereby making said relay slow to release and at armature 129 and its resting contact opens the circuit of relay 103. By the above circuit operations just described the circuits of the connector C² are now arranged to work as a local connector and not as a switching through connector. The operation of the connector is now the same as previously described with the exception of course, that relay 103 is not energized and therefore the line relay 100 is not disconnected. The line relay 100 feeds talking battery to the calling party. Talking battery for the called subscriber extends through the two windings of the busy relay as follows: ground at armature 113, working contact of armature 129 and said armature, armature 120, lower wind-

ing of busy relay 105, normally closed springs controlled by armature 118, working contact of armature 122 and said armature, armature 140, wiper 143, bank contact 146, over the subscriber's loop to bank contact 144, wiper 141, armature 135, armature 119 and its working contact, and upper winding of relay 105 to battery. It is immaterial whether the relay 105 energizes or not over the above traced circuit because the busy tone is disconnected by the operation of armature 122 of the ring cut-off relay. It will be noted that the busy relay 105 provides for giving the calling subscriber a busy tone and controls the switching through relay in case the line called is busy, is also included in the circuit for giving the calling subscriber a ring back tone when the called party is being rung, and also acts as the battery feed relay for feeding talking battery to the called subscriber on local calls.

The calling and called subscriber may now converse with each other as desired. When conversation is finished the replacement of the receiver by the called party is without effect. When the calling subscriber replaces his receiver the line and release relays 100 and 101, respectively, deenergize. The latter relay at armature 113 removes the locking ground whereupon the ring cut-off relay 104, relay 106 and switching relay 108 deenergize. At armature 114, release relay 101 completes a circuit for energizing the release magnet 110, whereupon the connector C² releases in the well known manner. The lineswitch of the calling subscriber and the selector are also released in the well known manner and all the apparatus included in establishing the connection is now returned to normal position.

Having described my invention, what I consider to be new and desire to have protected by Letters Patent will be pointed out in the appended claims.

What is claimed is:

1. In a telephone system, two exchanges, a two-way trunk line comprising only two conductors connecting said exchanges, said trunk line terminating in an incoming repeater and an outgoing repeater in each exchange, means for seizing the outgoing repeater in one exchange, means in said outgoing repeater for repeating impulses over the two conductors of said trunk line in series to the incoming repeater in the second exchange, a line relay in said incoming repeater having two windings through the medium of which operating current is normally connected to said trunk conductors, automatic switches in the second exchange, contacts on said line relay for repeating the impulses sent over said trunk line to operate said switches to complete a connection, and means controlled by the response of the called subscriber for disconnecting said line relay and

all battery connections from said trunk line during conversation.

2. In a telephone system, two exchanges, a two-way trunk line comprising only two conductors connecting said exchanges, said trunk line terminating in an incoming repeater and an outgoing repeater in each exchange, means for seizing the outgoing repeater in one exchange, means in said outgoing repeater for repeating impulses over the two conductors of said trunk line in series to the incoming repeater in the second exchange, a line relay in said incoming repeater having two windings through the medium of which operating current is normally connected to said trunk conductors, automatic switches in the second exchange, contacts on said line relay for repeating the impulses sent over said trunk line to operate said switches to complete a connection, means controlled by the response of the called subscriber for disconnecting said line relay and all battery connections from said trunk line during conversation, and means independent of control from said line relay and the called subscriber for maintaining said switches in operated position.

3. In a telephone system, two exchanges, a two-way trunk line comprising only two conductors connecting said exchanges, said trunk line terminating in an incoming repeater and an outgoing repeater in each exchange, means for seizing the outgoing repeater in one exchange, means in said outgoing repeater for repeating impulses over the two conductors of said trunk line in series to the incoming repeater in the second exchange, a line relay in said incoming repeater having two windings through the medium of which operating current is normally connected to said trunk conductors, automatic switches in the second exchange, contacts on said line relay for repeating the impulses sent over said trunk line to operate said switches to complete a connection, a back-bridge relay in said incoming repeater operated by the response of the called subscriber, said back-bridge relay feeding talking battery to the called subscriber, and means controlled by said last mentioned relay for disconnecting said line relay and all battery connections from said trunk line during conversation and for maintaining said switches in operated position independent of said line and back-bridge relays and the called subscriber.

4. In a telephone system, two exchanges, a two-way trunk line comprising only two conductors connecting said exchanges, said trunk line terminating in an incoming repeater and an outgoing repeater in each exchange, means for seizing the outgoing repeater in one exchange, means in said outgoing repeater for repeating impulses over the two conductors of said trunk line in series to the incoming repeater in the second exchange, a line relay

in said incoming repeater having two windings through the medium of which operating current is normally connected to said trunk conductors, automatic switches in the second exchange, contacts on said line relay for repeating the impulses sent over said trunk line to operate said switches to complete a connection, a back-bridge relay in said incoming repeater operated by the response of the called subscriber, said back-bridge relay feeding talking battery to the called subscriber, means controlled by said last mentioned relay for disconnecting said line relay and all battery connections from said trunk line during conversation and for maintaining said switches in operated position independent of said line and back-bridge relays and the called subscriber, and means controlled from said outgoing repeater for releasing said switches.

5. In a telephone system, two exchanges, a two-way trunk line comprising only two conductors for connecting said exchanges, means for seizing said trunk line at one exchange, an impulsing circuit including the two conductors of said trunk, the two windings of a line relay at the second exchange and battery and ground connections in series, automatic switches in the second exchange controlled by said impulse circuit to complete a connection, a talking circuit including the two conductors of said trunk line but excluding all battery and ground connections, and means controlled by the response of the called subscriber for automatically switching the two conductors of the trunk line from the impulsing circuit to the talking circuit.

6. In a telephone system, two exchanges, a two-way trunk line comprising only two conductors for connecting said exchanges, means for seizing said trunk line at one exchange, an impulsing circuit including the two conductors of said trunk, the two windings of a line relay at the second exchange and battery and ground connections in series, automatic switches in the second exchange controlled by said impulse circuit to complete a connection, a talking circuit including the two conductors of said trunk line but excluding all battery and ground connections, means controlled by the response of the called subscriber for automatically switching the two conductors of the trunk line from the impulsing circuit to the talking circuit, and means for feeding talking battery to the called subscriber over the talking conductors of said switches from a point between said trunk line and said switches.

7. In a telephone system, two exchanges, a two-way trunk line comprising only two conductors connecting said exchanges, said trunk line terminating in an outgoing repeater in one exchange and an incoming repeater at the other exchange, means for seizing said outgoing repeater, a line relay in

said incoming repeater having two windings through the medium of which operating current is normally connected to the conductors of said trunk line, an impulsing circuit including the windings of said relay and the conductors of said trunk line in series, a talking circuit including the conductors of said trunk line but excluding said line relay and all battery connections, automatic switches, means controlled by said line relay for operating said switches to complete a connection, and means controlled by the response of the called subscriber for automatically switching the conductors of said trunk line from said impulsing circuit to said talking circuit.

8. In a telephone system a local exchange, a distant exchange, a called line, a connector switch having a pair of talking conductors and a release trunk conductor, means including said connector for completing connections to said line from either said local exchange or said distant exchange, a line relay in said connector for feeding talking battery to a calling line on local connections, a busy relay in said connector for feeding talking battery to the called line on local connections, a switching relay in said connector when energized for switching the talking conductors of said connector straight through excluding all battery feed connections from said line and busy relays, a control relay permanently connected to the release trunk conductor of said connector which when energized renders said switching relay inoperative, means automatically controlled over said release trunk conductor for energizing said control relay on local calls and for short circuiting said control relay on inter exchange calls to render the same inoperative, and means independent of said connector for feeding talking battery to the called line on inter-exchange calls.

9. In an automatic telephone system, a calling subscriber's line and a called subscriber's line, subscriber controlled means including a repeater for use in setting up a connection between said subscribers' lines, said repeater feeding operating battery toward only the calling subscriber's line during the setting up of the connection, means in said repeater operative responsive to the completion of the connection to the called subscriber's line for feeding talking battery to the called subscriber's line, and means in said repeater controlled by the response of the called subscriber for disconnecting said operating battery extending toward the calling subscriber's line.

10. In an automatic telephone system, a calling subscriber's line and a called subscriber's line, subscriber controlled means including a repeater for use in setting up a connection between said lines, said repeater feeding operating battery toward the calling line but not the called line during the setting

up of the connection, a double wound relay in said repeater, means in said repeater operated responsive to the completion of the connection to the called subscriber's line for feeding talking battery to the called subscriber's line through the windings of said relay, said relay energized by the response of the called subscriber, and means in said repeater controlled by said relay for disconnecting said operating battery extending toward the calling subscriber's line.

11. In an automatic telephone system, a temporarily established connection including a trunk line, a repeater, and automatic switches, a differential relay in said repeater normally connecting battery and ground to the talking conductors of said trunk line, means for energizing said relay to disconnect the battery and ground connections from said trunk line, and means controlled over the talking conductors of said trunk for deenergizing said relay to release said switches.

12. In an automatic telephone system, a temporarily established connection including respectively, a calling subscriber's line, an outgoing impulse repeater, a trunk line, an incoming repeater, automatic switches, and means at said outgoing repeater controlled by the disconnection of the calling subscriber for momentarily connecting battery and ground, respectively, to the two talking conductors of said trunk line, and means in said incoming repeater responsive thereto to cause the release of said switches.

13. In an automatic telephone system, a temporarily established connection including, respectively, a calling line, a two conductor trunk, an incoming repeater, and a called line, a line relay in said repeater having two windings for feeding battery and ground to the two conductors of said trunk, respectively, a second relay having contacts for normally connecting the windings of said line relay to the conductors of said trunk, means controlled by the response of the called subscriber for energizing said second relay to disconnect said line relay and battery and ground connections from the conductors of said trunk, and means controlled by the calling subscriber for deenergizing said second relay to again connect said line relay and battery and ground connections to said trunk.

14. In an automatic telephone system, a temporarily established connection including, respectively, a calling line, a trunk line, a repeater, automatic switches, and a called line, a line relay in said repeater having two windings for normally feeding battery and ground to the talking conductors of said trunk line, a second relay in said repeater, a circuit for energizing said second relay when the called subscriber answers to disconnect the windings of said line relay and battery and ground from the talking conductors of said trunk line, means for reducing the

- flow of current in said circuit, and means controlled by the calling subscriber for de-energizing said second relay to release said switches.
15. In an automatic telephone system, a temporarily established connection including, respectively, a calling line, a trunk line, a repeater, automatic switches, and a called line, a line relay in said repeater having two windings for normally feeding battery and ground to the talking conductors of said trunk line, a differential relay in said repeater, a circuit for energizing said differential relay when the called subscriber an-
10. 15. 20. 25. 30. 35. 40. 45. 50. 55. 60. 65. 70. 75. 80. 85. 90. 95. 100. 105. 110. 115. 120. 125. 130.
- swers to disconnect the windings of said line relay and battery and ground from the talking conductors of said trunk line, and means controlled by the calling subscriber for de-energizing said differential relay to release said switches.
16. In an automatic telephone system, a temporarily established connection including, respectively, a calling line, a trunk line, a repeater, automatic switches, and a called line, a line relay in said repeater having two windings for normally feeding battery and ground to the talking conductors of said trunk line, a differential relay in said repeater, a circuit for energizing said differential relay when the called subscriber an-
10. 15. 20. 25. 30. 35. 40. 45. 50. 55. 60. 65. 70. 75. 80. 85. 90. 95. 100. 105. 110. 115. 120. 125. 130.
- swers to disconnect the windings of said line relay and battery and ground from the talking conductors of said trunk line, and means controlled by the calling subscriber to momentarily connect battery and ground to the talking conductors of said trunk line to cause said differential relay to deenergize and release said switches.
17. In an automatic telephone system, a temporarily established connection including, respectively, a calling line, a trunk line comprising only two conductors, an incoming repeater, and a called line, a line relay in said repeater having two windings for feeding battery and ground, respectively, to the two conductors of said trunk line, a differential relay having contacts for normally connecting the windings of said line relay to the conductors of said trunk line, a back bridge relay in said repeater for feeding talking battery to the called line, an energizing circuit for said differential relay includ-
10. 15. 20. 25. 30. 35. 40. 45. 50. 55. 60. 65. 70. 75. 80. 85. 90. 95. 100. 105. 110. 115. 120. 125. 130.
- ing contacts on said back bridge relay, said back bridge relay operated by the response of the called subscriber for closing said energizing circuit to cause said differential relay to energize and disconnect said line relay and battery and ground from the conductors of said trunk line, another circuit for said differential relay including the two conductors of said trunk line in series, and means controlled by the calling subscriber for closing said last mentioned circuit to cause said differential relay to deenergize and again connect said line relay and bat-
10. 15. 20. 25. 30. 35. 40. 45. 50. 55. 60. 65. 70. 75. 80. 85. 90. 95. 100. 105. 110. 115. 120. 125. 130.
- tery and ground connections to the conductors of said trunk line.
18. In an automatic telephone system, a temporarily established connection includ-
10. 15. 20. 25. 30. 35. 40. 45. 50. 55. 60. 65. 70. 75. 80. 85. 90. 95. 100. 105. 110. 115. 120. 125. 130.
- ing, respectively, a calling line, a trunk line comprising only two conductors, an incoming repeater, and a called line, a line relay in said repeater having two windings for feeding battery and ground, respectively, to the two conductors of said trunk line, a differential relay having contacts for normally connecting the windings of said line relay to the conductors of said trunk line, a back bridge relay in said repeater for feeding talking battery to the called line, an energizing circuit for said differential relay including contacts on said back bridge relay, said back bridge relay operated by the response of the called subscriber for closing said energizing circuit to cause said differential relay to energize and disconnect said line relay and battery and ground from the conductors of said trunk line, a deenergizing circuit for said differential relay including the two conductors of said trunk line in series, and means independent of said contacts in said energizing circuit for preventing the reenergization of said differential relay.
19. In a telephone system, two exchanges, a trunk line connecting said exchanges, means for seizing said trunk line in one exchange, a line relay in the trunk line at the second exchange having two windings through the medium of which operating current is normally connected to the conductors of said trunk line, automatic switches in the second exchange, contacts on said relay for controlling said switches to complete a connection, and means controlled by the response of the called subscriber for disconnecting said relay and all battery connections from said trunk line during conversation.
20. In a telephone system, two exchanges, a trunk line connecting said exchanges, means for seizing the trunk line in the first ex-
10. 15. 20. 25. 30. 35. 40. 45. 50. 55. 60. 65. 70. 75. 80. 85. 90. 95. 100. 105. 110. 115. 120. 125. 130.
- change, means for repeating impulses over said trunk line to the second exchange, a line relay in said second exchange having two windings through the medium of which operating current is normally connected to said trunk line, automatic switches in the second exchange, contacts on said line relay for repeating the impulses sent over said trunk line to operate said switches to complete a connection, a back bridge relay in said trunk line in the second exchange operated by the response of the called subscriber, said back bridge relay feeding talking battery to the called subscriber, and means controlled by said back bridge relay for disconnecting said line relay and all battery connections from said trunk line during conversation and for maintaining said switches in operated position independent of said line and back bridge relays and the called subscriber.

21. In a telephone system, two exchanges, a trunk line connecting said exchanges, means for seizing the trunk line in the first exchange, means for repeating impulses over said trunk line to the second exchange, a line 5 relay in said second exchange having two windings through the medium of which operating current is normally connected to said trunk line, automatic switches in the second exchange, contacts on said line relay for repeating the impulses sent over said trunk line to operate said switches to complete a connection, a back bridge relay in said trunk line in the second exchange operated by the 10 response of the called subscriber, said back bridge relay feeding talking battery to the called subscriber, means controlled by said back bridge relay for disconnecting said line relay and all battery connections from said 15 trunk line during conversation and for maintaining said switches in operated position independent of said line and back bridge relays and the called subscriber, and means controlled from the trunk line in the first exchange 20 for releasing said switches.
22. In a telephone system, a trunk line comprising only two conductors, means for seizing said trunk line, an impulsing circuit including, respectively, the two conductors of 25 said trunk line, the two windings of a line relay, and battery and ground connections in series, automatic switches controlled by said impulse circuit to complete a connection, a talking circuit including the two conductors of said trunk line but excluding said line 30 relay and all battery and ground connections, means controlled by the response of the called subscriber for automatically switching the conductors of said trunk line from the impulsing circuit to the talking circuit, and means controlled by the calling subscriber for 35 connecting battery and ground to said talking circuit.
23. In an automatic telephone system, a 40 trunk line, automatic switches, means controlled over said trunk line for operating said switches, a relay in said trunk line normally connecting battery and ground to the talking conductors of said trunk line, means for energizing said relay to disconnect all battery and 45 ground connections from said trunk line, and means controlled over the talking conductors of said trunk line in series for deenergizing said relay to release said switches.
24. In an automatic telephone system, a 50 temporarily established connection including respectively, a calling subscriber's line, a two conductor trunk line, and step by step automatic switches, means controlled responsive 55 to the calling subscriber replacing his receiver for momentarily connecting battery and ground, respectively, to the two talking conductors of said trunk line, and a relay controlled by said momentary connection of 60 battery and ground over the two conductors

of said trunk line in series to cause the release of said switches.

25. In an automatic telephone system, a two conductor trunk line, automatic switches, means controlled over said trunk line for operating said switches to extend a connection, a differential relay in said trunk line energized over a local circuit including one winding of said relay, means controlled by said relay for maintaining said switches in operated position, and means for deenergizing said relay over a circuit including a second winding of said relay and the two conductors of said trunk line in series to cause the release of said switches. 70

26. In a telephone system, two exchanges, a two-way trunk line connecting said exchanges and terminating in each exchange in a dry trunk repeater, said dry trunk repeaters normally connecting battery and ground 75 to the conductors of said trunk line, and means in said repeaters for controlling the disconnection of all battery and ground connections from the conductors of said trunk line during conversation. 80

27. In a telephone system, a trunk, a calling and a called line, means for extending a connection from said calling line to said called line via said trunk, means for answering the call, a relay comprising two opposing windings, means responsive to the answering of the call for closing a circuit for one winding of said relay to operate the relay, and means responsive to the calling party disconnecting for closing a circuit for the other winding of said relay whereby the relay is 90 deactuated. 95

28. In a telephone system, a trunk, a calling and a called line, means including an impulsing relay bridged across the conductors of said trunk for extending a call from said calling line to said called line, a relay comprising two opposing windings, means responsive to the called party answering the call for closing a circuit for one winding of 100 said relay whereby the relay energizes, disconnects said impulsing relay from the trunk and connects its own other winding thereto, and means responsive to the calling party disconnecting for closing a circuit for the 105 other winding of said relay whereby the relay deactuates and releases the connection. 110

29. In a telephone system, an incoming trunk, an outgoing trunk, a repeating coil comprising a plurality of windings inductively connecting said trunks, an impulsing circuit including conductors of said incoming trunk and windings of said repeating coil, a control circuit including conductors of 115 said outgoing trunk and other windings of 120 said repeating coil, and means responsive to the transmission of impulses over said impulsing circuit for short circuiting the windings of said repeating coil in both the impulsing and control circuits. 125

30. In a telephone system, an incoming trunk, a repeating coil comprising a plurality of windings, an impulsing circuit normally including windings of said repeating coil serially connected in the conductors of said trunk, an outgoing trunk, a control circuit including other windings of said repeating coil bridged in series across the conductors of said outgoing trunk, and means responsive to the transmission of impulses over said impulsing circuit for establishing an alternate impulsing circuit excluding the windings of said repeating coil and for short circuiting the windings bridged across the conductors of said outgoing trunk.

10 In witness whereof, I hereunto subscribe my name this 14th day of April, A. D. 1927.
CLARENCE E. LOMAX.
